UNITED STATES PATENT OFFICE.

SAMUEL J. SILBERMAN, OF NEW YORK, N. Y.

MEMORANDUM-BOOK AND PAD.

SPECIFICATION forming part of Letters Patent No. 294,920, dated March 11, 1884.

Application filed June 21, 1883. (Model.)

To all whom it may concern:

Be it known that I, SAMUEL J. SILBERMAN, of the city, county, and State of New York, have invented a new and Improved Memorandum-Book and Pad, of which the following is a full, clear, and exact description.

This invention has for its object to provide an improvement in merchants' self-copying memorandum-books and pads; and it consists 10 of the combination of parts, substantially as hereinafter fully set forth, and pointed out in the claims.

Reference is to be had to the accompanying drawings, forming part of this specification, 15 in which similar letters of reference indicate corresponding parts in all the figures.

Figure 1 is a perspective view of my self-copying memorandum-book as it appears when closed. Fig. 2 is a plan view, showing 20 the book open and the carbon paper and memorandum-slip in position for writing the memorandum. Fig. 3 is a plan view of the book and carbon-paper attachment opened out, showing the construction of the attachment; and Fig. 4 is a perspective view, on a 25 reduced scale, of the carbon-paper attachment, showing the memorandum-book and pad attached in dotted lines.

The book A is a plain memorandum-book, 30 of ordinary size—preferably of a size adapted to be carried in the coat-pocket. The slip pad or tablet B is attached, by any suitable means, to the cover a of the book, outside, so that the book and pad are as one. The cover 35 b of the book is formed or provided with the carbon-paper attachment C. In this instance this attachment C is composed of the heavy-paper flap d, that is attached to the cover b of the book by the rivets or eyelets c c', the 40 leaf f, that is a trifle wider than the leaves of the memorandum-book, and the frame g, that holds the sheet h of carbon-paper. The frame g is adapted to fold back upon the leaf f, and leaf f is adapted to be folded in between the leaves of the book, as shown in 45 Fig. 1, so that when the book is closed leaf f, with frame g and carbon-paper h, serve as a book-mark, enabling the memorandum-book always to be opened at the right place, and 50 the leaf f serves also to always hold the sheet h of carbon-paper in its proper place, so that when the book is opened for making a memorandum it is only necessary to tip the frame g over upon the right-hand side of the book,

to bring the carbon-paper into position for 55 use, as will be understood from Fig. 4. The book being open and the sheet of carbon-paper h turned upon the right-hand side of the book, in making the memorandum, slip b², taken from the pad B, will simply be placed 60 upon the sheet of carbon-paper h, as shown in Fig. 2, and the memorandum written upon the slip with an ordinary lead-pencil. The memorandum will be impressed or written through the carbon-paper upon the leaf of the book 65 in exact fac-simile of the memorandum on the slip, as shown in Figs. 2 and 3. The frame g and leaf f will then be raised off from the leaves of the book sufficiently to permit the sheet having the memorandum just written 70 upon it to be turned. Then the book will be closed upon the leaf f, carbon-sheet h, and frame g to the position shown in Fig. 1, and placed in the pocket ready for the next entry.

It will thus be seen that the book is very 75 convenient and easily used, and that by the use of the frame g the carbon-paper is always held in the flat position and prevented from folding.

The frame g may be made of metal, hinged 80 at g' g', and attached to the leaf f by the rivets or eyelets g² g²; or it may be made of leather or of paper, or of any other suitable material. If made of heavy paper, or of the same material as the leaf f, it may be made a part of the leaf; 85 and if the frame g and leaf f are both made of the same material as the cover b of the book, the cover, leaf, and frame might all be made in one piece.

The carbon-paper will be attached to the 90 frame g with cement or in any other suitable manner.

Having thus described my invention, what I 95 claim as new, and desire to secure by Letters Patent, is—

1. The combination, with a memorandum-book, of the heavy-paper flap d, rivets or eyelets c c', a leaf, f, wider than the book-leaves, and the frame g, carrying a carbon-sheet, as described.
2. The book A, having pad B attached to one of its covers, in combination with the carbon-paper attachment C, attached to the other cover, substantially as described.

SAMUEL J. SILBERMAN.
